UNITED STATES PATENT OFFICE.

CHARLES S. HUNTINGTON, OF LOS ANGELES, CALIFORNIA.

LOCK.

SPECIFICATION forming part of Letters Patent No. 703,927, dated July 1, 1902.

Application filed July 30, 1901. Serial No. 70,286. (No model.)

To all whom it may concern:

Be it known that I, CHARLES S. HUNTINGTON, a citizen of the United States, residing at Los Angeles, in the county of Los Angeles and State of California, have invented a new and useful Door-Lock, of which the following is a specification.

The invention relates to improvements in door-locks.

10 The object of the present invention is to improve the construction of door-locks and to provide a simple and comparatively inexpensive one adapted to serve as a latch and capable of being locked and unlocked from the interior by the inner knob and of being locked from the exterior by the outer knob, so that a key will be required to unlock it from the exterior.

20 A further object of the invention is to provide a lock of this character which when locked by the inner knob will effectually prevent the introduction of a key from the exterior.

The invention consists in the construction 25 and novel combination and arrangement of parts hereinafter fully described, illustrated in the accompanying drawings, and pointed out in the claims hereto appended.

In the drawings, Figure 1 is a perspective 30 view of a lock constructed in accordance with this invention, the face-plate being removed and the knobs being detached. Fig. 2 is a horizontal sectional view. Fig. 3 is a vertical sectional view. Fig. 4 is a detail view of 35 the catch or tumbler. Fig. 5 is a similar view of the outer hub or sleeve. Fig. 6 is a detail view of the inner and outer knobs and the connecting-spindle. Fig. 7 is a detail view illustrating the construction for securing 40 the inner knob to the spindle. Fig. 8 is a detail view of the cylindrical sleeve. Fig. 9 is a similar view of the rectangular sleeve. Fig. 10 is a detail perspective view of the face-plate of the lock-casing when the latter 45 is constructed for use as a rim-lock. Fig. 11 is a detail view of the keeper. Fig. 12 is a detail view of the outer door-plate or escutcheon, illustrating the construction of the latch for limiting the movement of the outer knob. 50 Fig. 13 is a detail view of the sliding keyhole-guard. Fig. 14 is a detail view of the key.

Like numerals of reference designate cor-

responding parts in all the figures of the drawings.

1 designates a lock-casing, which when the 55 lock is designed for use as a rim-lock is provided with a removable face-plate 2, but which may be constructed for use as a mortise-lock, as illustrated in Figs. 2 and 3 of the accompanying drawings. The lock may 60 be made either right or left hand, and the back or body of the casing is provided with a lower side 3 and a rear side or flange 4. The removable face-plate 2 is provided with a top side 5, a front side 6, and a rear side or 65 flange 7, which completes the back of the casing. The rear side or flange 7 is provided with an extension 8, and the top side 5 is provided near the front end of the casing with a similar extension 9. These extensions 8 and 9 are 70 perforated for the reception of screws or other suitable fastening devices for securing the lock to the door. The front side 6 is extended and is adapted to be arranged on the front edge of the door and is perforated for the 75 reception of a suitable fastening device for securing it to the same. The back of the casing is provided with a post 10, having a threaded socket for the reception of a screw or other suitable fastening device for securing 80 the face-plate to the back of the casing. The lock-casing, which may be constructed in any other suitable manner, is provided at its front with an opening 11 for the reception of the outer end of a bolt 12, having a limited 85 reciprocation to enable it to serve the purposes of a latch and capable of being extended to operate as a locking-bolt.

The bolt, which has its body portion located between the post 10 and the top of the casing, 90 has its front portion enlarged and is provided thereat with a depending arm 13, and it has a beveled nose 14, adapted to engage a keeper 15, whereby when the door is closed the bolt, which is spring-actuated, is reciprocated or 95 moved inward and is caused to engage the keeper automatically, the spring throwing the bolt outward into engagement with the keeper after the nose 14 has passed the front of the said keeper. The keeper may be constructed in any suitable manner and is provided at its front with a curved flange or extension 16, forming a curved loop and arranged to be engaged by the end of the bolt. 100

One end of the loop is formed integral with the keeper, and the other end is suitably secured to the same, preferably by means of a tongue, as indicated in Fig. 11 of the drawings. The arm 13, which depends from the front of the bolt, is adapted to be engaged by a key 17 to unlock the door from the exterior thereof. The arm 13, which is arranged vertically, is provided at its front edge with an inwardly-extending horizontally-disposed lug 18, arranged to be engaged by the front or outer end of a catch or tumbler 19.

The bolt is provided at its inner end with recesses 20 and 21, forming inner rear shoulders adapted to be engaged by inner and outer hubs or sleeves 22 and 23, mounted on a transverse spindle 24 and connected by the means hereinafter described with inner and outer knobs 25 and 26 and adapted to be operated by the same. The outer hub or sleeve 23 is provided with four diametrically arranged arms or lugs 27, having rounded outer ends and adapted to engage either the inner end of the bolt or the shoulder formed by the outer recess 21 of the said inner end of the bolt. When the outer knob is rotated backward, one of the lugs is carried into engagement with the shoulder formed by the recess 21, and the bolt is moved inward against the action of the spring 28 to disengage it from the keeper. When the outer knob is rotated forwardly, one of the lugs or arms 27 is carried into engagement with the rear end of the bolt, which is thrown forward beyond the reach of the lugs or arms 27, so that after such operation the bolt cannot be retracted by operating the outer knob.

The lug or projection 18 of the depending arm 13 is located beneath the outer arm or portion 29 of the catch or tumbler, which is provided at its outer end with a bend forming an inclined portion 30 and a vertical portion 31. The inclined portion presents an inclined lower face to the arm or lug 18, and when the bolt is moved outward by the outer knob the lug or arm 18 moves outward and lifts the outer arm or portion of the catch or tumbler and passes beyond the vertical portion 31, which drops behind the said lug or projection 18 and locks the bolt against inward movement. The front arm or portion of the catch or tumbler is held in engagement with the lug or projection 18 by the spring 28.

The catch or tumbler 19 is provided between its ends with a perforated ear and is pivoted to the back of the casing by a rivet 32 or other suitable fastening device. The rear arm or portion 33 of the catch or tumbler is angularly bent and laterally offset from the plane of the perforated ear, and it is provided with openings 34 and 35. The spring 28, which is disposed longitudinally of the casing, has its inner or rear end supported by a flange or projection 36, and it extends upward through the opening 34 and engages the rear arm or portion of the catch or tumbler at the top of the opening, whereby the

outer or front arm or portion 29 is thrown downward and is held in engagement with the lug or projection 18 of the bolt.

The inner hub or sleeve 22 is provided with front and rear upper arms or lugs 37 and 38, arranged to engage the bolt, as clearly shown in Fig. 1. The arm or lug 38 is adapted to engage the rear end of the bolt to throw the same forward to lock the door from the interior by rotating the inner knob, and the arm or lug 37, which is adapted to engage the shoulder formed by the recess 20 to move the latch-bolt inward, is enlarged or extended and is of greater length than the lugs or arms 27 of the outer sleeve or hub in order to enable the bolt to be unlocked from the interior by rotating the inner knob backward. The inner hub or sleeve is also provided with a depending arm 39, arranged to engage the rear arm or portion of the tumbler or catch to lift the front or outer arm of the same out of engagement with the laterally-extending lug or projection of the bolt to release the latter to permit the said bolt to be moved inward by the arm or lug of the inner hub or sleeve.

The depending arm or lug 39 is provided with a recess 40, forming a shoulder to engage the upper edge of the pivoted tumbler or catch and providing an extension which is adapted to engage and reciprocate a sliding guard 41. The rear portion or arm of the tumbler or catch is provided with a lateral projection or lug 42, extending beneath the flange or support 36 and limiting the upward movement of the said inner arm or portion of the tumbler to prevent the same from being displaced by the action of the spring 28.

The sliding keyhole-guard, which is provided with a solid front portion or block 43, has a recess 44 at its rear portion, forming opposite shoulders to be engaged by the depending lug or arm of the sleeve or hub 22. When the depending arm of the inner hub or sleeve swings rearward, it engages the rear shoulder or wall formed by the recess 44, and when it is moved forward it engages the front wall of the same. The solid portion or block 43 at the front end of the sliding guard is adapted to be carried by such inward movement to a point directly opposite the keyhole 45, whereby when the door is locked from the interior by rotating the inner knob it will be impossible to introduce a key or instrument into the lock from the exterior. The sliding keyhole-guard is locked against movement by means of an L-shaped arm or lug 46, extending upward and laterally from the inner or rear portion of the guard and adapted to be carried in advance and in rear of a projection or lug 47, extending upward from the bottom of the opening 35 of the rear portion of the catch or tumbler. The rear portion of the catch or tumbler is depressed, while the projection or lug of the sliding keyhole-guard is reciprocated backward and forward.

The key which is employed for unlocking the door from the exterior after the same has

been locked by the knob 26 is provided with a tubular portion or barrel 48, which is adapted to fit over a rounded stud 49, carried by the sliding keyhole-guard and located opposite the keyhole when the said guard is at the limit of its outward movement. The guard is provided with projections 50, 51, and 52, arranged as clearly illustrated in Fig. 13 of the accompanying drawings. The key is notched, as shown in Fig. 14, to correspond to the projections 50, 51, and 52, and these may be arranged in a variety of different positions to change the character of the key, as will be readily apparent. When it is desired to unlock the door from the exterior, the key is inserted in the lock and when turned engages and lifts the front or outer portion of the catch or tumbler and reciprocates the bolt by engaging the depending arm 13. This movement carries the bolt rearward sufficiently to bring the rear end of the same within reach of the arms or lugs 27 of the outer hub or sleeve, which is then partially rotated by the outer knob to complete the unlocking operation. The front portion of the spring 28 extends upward beyond the front arm or portion of the tumbler or catch and engages a shoulder 53, formed by the enlarged front portion of the bolt. The enlarged front portion of the bolt lying in rear of the beveled nose is carried outward into engagement with the keeper by the locking operation. The outer knob is provided with a shank having portions 54 and 55, the outer portion 55, or that portion lying farther from the inner face of the knob 26, being of less diameter than the inner portion 54 and extending well into the door to conceal the screw 56 to prevent the outer knob from being removed from the exterior after the parts have been assembled. The inner portion 54 is provided with a pair of oppositely-disposed ribs 57, forming shoulders adapted to be engaged by a latch 58, which is pivotally mounted on an outer door-plate or escutcheon 59, which is suitably secured to the door. The outer door-plate or escutcheon is provided with a key-hole 60, and it preferably has a flange 61 at its outer end, and this flange 61 is designed to be arranged at the outer or free edge of the door and may be provided with a spur or projection, as indicated in Fig. 12. The inner portion of the plate 59 is provided with an opening to receive the shank of the knob, and the latch, which is located above the opening and beneath a stop 59^a, is pivoted at its inner or lower end 62, and its outer or free portion, which is adapted to rest upon the shank of the outer knob, is provided with a shoulder 63 for engaging the ribs 57. The latch prevents the outer knob from being turned forwardly sufficiently to lock the door. The outer knob, when the latch is in engagement with it, is adapted to be partially rotated to impart to the bolt a limited reciprocation to engage its beveled nose with the keeper and to disengage it therefrom, and the spring will

operate to throw the bolt outward. When it is desired to lock the door from the exterior, the latch is raised and the outer knob is turned forwardly to carry one of the lugs or arms 27 into engagement with the rear end of the bolt. This throws the bolt forward or outward, as before explained.

The shank of the outer knob is provided with a circular bore or opening to receive the spindle 24, and the inner knob, which is provided with a shank 64, has a rectangular opening to receive the inner end of the spindle, which is provided with exterior screw-threads 80 65 and which has an interiorly-threaded socket 66. The knob 25 is provided at its outer face with a socket to receive a cylindrical nut 67, which engages the exterior screw-thread 65 and which is engaged by the thread of a screw 68. The screw 68 engages the interior screw-threads of the socket of the inner end of the spindle and retains the nut in place. One set of screw-threads is designed to be right-hand and the other left-hand, so that the nut and the screw will operate as a lock.

The outer portion of the shank 64 of the inner knob is provided with a rectangular opening for the reception of a rectangular sleeve 69, which is adjustably secured to the knob 95 and which fits within a rectangular opening 70 of the inner hub or sleeve, whereby the latter is interlocked with the inner knob and is adapted to be rotated by the same. The rectangular sleeve is provided with apertures 71, 100 adapted to be engaged by a screw 72 to permit the parts to be adjusted to suit the thickness of a door, and the screw 56 is also adapted to permit the parts to be adjusted for that purpose. The inner knob is arranged on a 105 cylindrical sleeve or barrel 73, extending entirely through the inner knob to the nut and interposed between the latter and the outer hub or sleeve and provided adjacent to the same with a recess 74. The recess 74, which 110 is formed by cutting away the inner end of the cylindrical sleeve or barrel, receives a curved flange 78 of a bracket 79. The curved flange 78, which extends laterally from the bracket 79, completes the inner end of the 115 cylinder or barrel 73, and the bracket 79, which is secured to the rear wall of the lock-casing, is interposed between the inner and outer hubs or sleeves. The rear end of the bracket is provided with a flange, which is perforated 120 for the reception of suitable fastening devices for securing the bracket to the lock-casing.

It will be seen that the lock is simple and comparatively inexpensive in construction, 125 that it is adapted to be locked and unlocked from the interior by the inner knob and from the exterior by the outer knob and a key, and that when locked from the interior by the inner knob the keyhole is automatically closed 130 by the guard to prevent a key or instrument from being introduced into the lock from the exterior. Also it will be seen that the lock cannot be unlocked from the exterior by the

outer knob, and that the pivoted latch limits the forward movement of the outer knob to prevent the lock from being accidentally locked by the outer knob, and that the knobs 5 are independently movable and do not affect the rotation of each other.

The sliding spring-actuated bolt has a limited reciprocation to serve as a latch and an extended reciprocation to operate as a locking-bolt, and the catch or tumbler permits a free reciprocation of the bolt when the latter operates as a latch and is capable of locking the bolt in its extended position.

What I claim is—

15 1. In a lock, the combination of a sliding bolt capable of a limited reciprocation to operate as a latch, and adapted also to have an increased or extended reciprocation to serve as a locking-bolt, and the independently-movable inner and outer knobs provided with means for actuating the said bolt, substantially as described.

25 2. In a lock, the combination of a sliding bolt having a limited reciprocation to form a latch and capable also of an increased or extended reciprocation to serve as a locking-bolt, a spring for automatically moving the bolt outward when the same operates as a latch, an outer knob, and a hub or sleeve connected with the outer knob and provided with lugs arranged to move the bolt inward against the action of the spring, and adapted to throw the bolt outward to its extended position, said bolt, when extended, being arranged beyond 35 the reach of the said lugs, substantially as described.

3. In a lock, the combination of a sliding spring-actuated bolt having a limited reciprocation to operate as a latch and capable of increased or extended reciprocation to operate as a locking-bolt, said bolt being provided near its rear end with a shoulder, a hub or sleeve provided with lugs arranged to engage the shoulder to move the bolt backward 45 against the action of the spring, said lugs being also arranged to engage the rear end of the bolt to throw the latter to its extended position beyond the reach of the said lugs, and means for operating the hub or sleeve, 50 substantially as described.

4. In a lock, the combination of a sliding spring-actuated bolt, capable of a limited reciprocation to operate as a latch and of an extended reciprocation to serve as a locking-bolt and provided with a key-engaged portion 55 adapted to enable it to be returned from its extended position, and a hub or sleeve provided with a lug arranged to move the bolt inward against the action of the spring and 60 adapted to throw the bolt outward to its extended position, substantially as described.

5. In a lock, the combination of a sliding bolt capable of a limited reciprocation to form a latch and of an extended reciprocation to 65 serve as a locking-bolt, an outer knob, a hub or sleeve connected with the outer knob and provided with a lug arranged to engage the

bolt to move the same inward against the action of the spring, and adapted to throw the bolt outward to its extended position, said 70 bolt, when extended, lying beyond the reach of the lug, and means for limiting the forward rotation of the outer knob to prevent the bolt from being accidentally thrown to its extended position, substantially as described. 75

6. In a lock, the combination of a sliding bolt, capable of a limited and of an extended reciprocation, an outer knob, a hub or sleeve connected with the outer knob and provided with a lug arranged to engage the bolt to 80 move the same inward against the action of the spring and adapted to throw the bolt to its extended position, and a movable latch arranged to engage the knob, to limit the forward rotation thereof, substantially as and 85 for the purpose described.

7. In a lock, the combination of a sliding bolt having a limited and an extended reciprocation, an outer knob provided at its shank with a shoulder, a hub or sleeve having a lug 90 arranged to throw the bolt to its extended position, a latch pivotally mounted adjacent to the outer knob and arranged to engage the shoulder to limit the forward rotation of the said knob, and adapted to be lifted out of 95 such engagement, and a stop for limiting the movement of the latch, substantially as described.

8. In a lock, the combination of a sliding spring-actuated bolt capable of a limited reciprocation to form a latch and of an extended reciprocation to operate as a locking-bolt, a spindle extending through the lock, an inner knob arranged on the inner portion of the spindle, an outer knob arranged on the 105 outer portion of the spindle, and a hub or sleeve connected with the inner knob and provided with lugs or arms arranged to engage the bolt and adapted to move the same to any of its positions, substantially as described. 110

9. In a lock, the combination of a sliding spring-actuated bolt capable of a limited and of an extended reciprocation, the spindle extending entirely through the lock, the independently-movable inner and outer knobs arranged on the inner and outer portions of the spindle, the outer hub or sleeve connected with the outer knob and having a lug adapted to move the bolt inward against the action 120 of the spring, and capable of throwing the bolt to its extended position, and an inner hub or sleeve connected with the inner knob and provided with lugs arranged to move the bolt to any of its positions, substantially as described. 125

10. The combination in a lock, of a sliding spring-actuated bolt capable of a limited and an extended reciprocation and provided at its back with recesses 20 and 21, forming shoulders, the independently-movable inner and outer knobs, the outer hub or sleeve connected with the outer knob and provided with lugs arranged to engage the bolt at the recess 130

21 and adapted to move the same inward against the action of the spring, and capable of throwing the bolt to its extended position beyond the reach of the lugs, and an inner 5 hub or sleeve connected with the inner knob and provided with a lug for throwing the bolt outward, and having an extended lug operating in the recess 20, and adapted to return the bolt from its extended position, substantially as described.

11. The combination of a sliding spring-actuated bolt capable of a limited and of an extended reciprocation, the independently-movable inner and outer knobs, the outer hub or 15 sleeve connected with the outer knob and having a lug for throwing the bolt to its extended position, an inner hub or sleeve having lugs for engaging the bolt, one of the lugs of the inner hub or sleeve being extended to 20 return the bolt from its extended position, and an arm carried by the bolt and arranged to be engaged by a key, whereby the bolt is returned from its extended position at the exterior of a door, substantially as described.

25 12. In a lock, the combination of a sliding bolt capable of a limited and an extended reciprocation to enable it to operate either as a latch or as a locking-bolt, a spring engaging the bolt and adapted to throw the same outward when the bolt operates as a latch, a catch or detent arranged to lock the bolt in its extended position and capable of permitting a free reciprocation of the bolt when the same operates as a latch, and means for actuating the bolt, substantially as described.

35 13. In a lock, the combination of a sliding spring-actuated bolt capable of a limited and of an extended reciprocation to enable it to operate either as a latch or as a locking-bolt, the 40 independently-movable inner and outer knobs provided with means for actuating the bolt, and a catch or detent arranged to lock the bolt in its extended position and capable of permitting a free reciprocation of the bolt when the latter is operated as a latch, substantially as described.

45 14. In a lock, the combination of a sliding spring-actuated bolt, capable of a limited and of an extended reciprocation, the independently-movable inner and outer knobs provided with means for actuating the bolt, an arm carried by the bolt and arranged to be engaged by a key to return the bolt from its extended position, and a catch or detent arranged to lock the bolt in its extended position, substantially as described.

55 15. In a lock, the combination of a sliding bolt capable of a limited and of an extended reciprocation and provided with a key-engaged arm and having a lug or projection, a catch or detent movably mounted and provided with a shoulder for engaging the lug or projection to lock the bolt in its extended position, said catch or detent being also provided

65 adjacent to the shoulder with an inclined face arranged to be engaged by the lug or projection to enable the bolt in moving outward to

lift the catch or detent, and means for actuating the bolt, substantially as described.

16. In a lock, the combination of a sliding 70 spring-actuated bolt capable of a limited and of an extended reciprocation to enable it to operate either as a latch or as a locking-bolt, said bolt being provided with a depending key-engaged arm having a laterally-extending lug, and a catch or detent movably mounted and provided at its outer portion with a bend forming an outer shoulder and providing an inclined face, said shoulder and inclined face being located beyond the lug, 80 when the bolt operates as a latch, substantially as described.

17. In a lock, the combination of a sliding 85 spring-actuated bolt, capable of a limited and an extended reciprocation to operate either as a latch or as a locking-bolt, a catch or detent pivoted between its ends and having its outer portion arranged to engage the bolt to lock the latter in its extended position, and a spring engaging the inner portion of the catch 90 or detent and also engaging the bolt, substantially as described.

18. In a lock, the combination of a sliding 95 spring-actuated bolt, capable of an extended and a limited reciprocation and provided with a depending key-engaged arm having a laterally-extending lug, a catch or detent pivoted between its ends and provided at its outer portion with a shoulder for engaging the lug to lock the bolt in its extended position, said 100 catch or detent having its outer arm located above the said lug and provided with an inclined face to enable the lug to lift it automatically when the bolt is moved outward, and means for actuating the bolt and for holding the catch or detent in its engaging position, substantially as described.

19. In a lock, the combination of a sliding 110 spring-actuated bolt having a limited and an extended reciprocation and provided with a depending key-engaged arm having a laterally-extending lug, a catch or detent pivoted between its ends and having its outer arm located above the lug and adapted to engage the same to lock the bolt in its extended position, said catch or detent having its inner 115 portion laterally offset and provided with an opening, a spring extending through the opening and engaging the inner arm of the catch or detent, and also engaging the shoulder of the bolt, and nuts for actuating the bolt, substantially as described.

20. In a lock, the combination of a sliding bolt, a knob-spindle, a catch or detent arranged to lock the bolt in its extended position, a movable keyhole-guard, a sleeve or hub arranged on the knob-spindle and provided with means for operating the bolt and arranged to engage both the catch or detent and the keyhole-guard, substantially as described.

21. In a lock, the combination of a reciprocating bolt, a sliding keyhole-guard, a catch or tumbler pivoted between its ends and ar-

ranged to engage the bolt and the keyhole-guard, and a hub or sleeve provided with means for actuating the bolt and the keyhole-guard and for swinging the catch or tumbler out of engagement with the same, substantially as and for the purpose described.

22. In a lock, the combination of a reciprocating bolt provided with a key-engaged portion, a catch or tumbler pivoted between its ends and provided at its front end with means for locking the bolt in its extended position, and having a projection at its rear portion, a sliding keyhole-guard provided with a recess and having a lug arranged to be engaged by the projection of the catch or tumbler, and a hub or sleeve provided with means for actuating the bolt and having an arm or lug arranged to engage the catch or tumbler and adapted to operate in the said recess to engage the opposite walls thereof to reciprocate the keyhole-guard, substantially as described.

23. In a lock, the combination of a casing, a sliding bolt, inner and outer hubs or sleeves provided with means for engaging the bolt, a spindle extending through the hubs or sleeves and engaging the outer one, a bracket mounted on the casing and extending be-

tween the hubs or sleeves and having a curved flange, a cylindrical sleeve or barrel arranged on the spindle and interlocked with the said flange, inner and outer knobs capable of independent rotation, and a polygonal sleeve connected with the inner knob and interlocked with the inner hub or sleeve, substantially as described.

24. In a lock, the combination of a casing, a reciprocating bolt, inner and outer hubs or sleeves provided with means for engaging the bolt, a spindle extending through the hubs or sleeves, the inner and outer knobs capable of independent movement, the outer knob being provided with an extended shank having a concealed portion secured to the spindle, said knobs being connected with the inner and outer sleeves or hubs, and means for securing the inner knob to the spindle, substantially as described.

In testimony that I claim the foregoing as my own I have hereto affixed my signature in the presence of two witnesses.

CHARLES S. HUNTINGTON.
